UNITED STATES PATENT OFFICE

2,510,293

SEATS, TABLES, AND THE LIKE

George Frederick Reed and William Henry Gould,
Johannesburg, Transvaal, Union of South
Africa

Application February 20, 1945, Serial No. 578,860.
In the Union of South Africa February 22,
1944

3 Claims. (Cl. 155—123)

1

This invention relates to seats or tables fitted with occasional rests adapted to be normally stowed away and to a large extent out of sight, but also adapted to be manually extended when desired and then to support light articles.

According to the invention the occasional rest when in its extended position constitutes a horizontal tray characterised by suitability for supporting light articles, having a continuous rim for retaining such articles on the floor of the tray, and extending from the chair or table at a position within easy reach of a person sitting in the seat or at the table. In its stowed position the rest is substantially within the periphery of the seat or table and exposes so little of its own structure as to be of insignificant appearance and is without interference with the normal use of the seat or table.

In some cases the tray is in one rigid piece and so associated with the seat or table as to be movable bodily between stops that determine its extended and its stowed positions.

In other cases the tray is in two parts so hinged to one another as to form two leaves capable of being folded together. In this case one leaf is rigid with the article of furniture; the other leaf, when folded, lying over the fixed leaf and, when extended, providing with the fixed leaf the continuous horizontal floor of the tray. The hinge axis is about level with what is the upper edge of the rim when the rest is extended.

When the tray is in one rigid piece, a side surface of the seat or table is formed with an orifice and the tray, forming a terminal portion of a member of general flat form, is arranged to be projected or retracted through said orifice while the rest of the member is retained within the orifice by the stops. The means for engaging the rest of the member to support the extended tray in its horizontal position may be provided within the orifice and may constrain the member for movement within its own plane. In an alternative arrangement the seat or table provides an internal chamber of such form that said member gravitationally rests in it in a position in which the floor of the tray has a substantial vertical direction component. The tray may be provided with an end surface that occupies the orifice when the tray is stowed.

In the case of a seat comprising a side arm the occasional rest is positioned on the arm at or towards the front end thereof and so as when extended to project outwardly from said arm, that is away from the seat. The above described hinged rest in this case has one leaf fixed to the

2

arm in a horizontal position and the folded tray constitutes the outer and upper corner of the arm. The fixed leaf is, in elevation, stepped down from the adjacent upper surface of the arm, and the other leaf, when stowed by folding over the fixed leaf, fills the step and presents its back surface in continuation of said adjacent upper surface of the arm. For the sake of appearance it is desirable that the back surface of the folding leaf should accord in appearance with the remainder of the arm.

Preferably the fixed leaf is structurally separate from the arm structure and is fixed to the latter. One use of this arrangement is for dealing with the cut edges of the upholstery around the fixed leaf when the arm is upholstered.

Said cut edges are hidden by said fixed leaf, and the back and side surfaces of the folding leaf of the tray are covered with upholstery the cut edges of which are similarly concealed by said leaf.

A card table according to this invention has several rests as described fitted to different edges of the table so that the extended trays project from said edges. When the rest consists of a folding tray, the fixed leaf is sunk below the table surface and the other leaf when folded provides its back as a continuation of the table surface. The rest for each table edge is positioned near to the left hand edge of such edge so as to be accessible to the right hand of a person who sits facing the edge to the left of the edge to which the rest is fitted.

According to a further feature of the invention, an arm chair is provided with a folding tray as described at the end of each of its arms. A table comprising a body that spans the chair arms is provided with two feet shaped to fit in the open trays.

Examples of the invention are illustrated in the accompanying drawings in which

Figure I shows a portion of an arm chair or settee fitted with a folding tray according to the invention.

Figure II is a vertical section through the arm of the chair with the tray folded.

Figure III shows a folding tray fitted to a card table, with the tray extended.

Figure IV is a similar view of the same form with the tray folded.

Figure V is a vertical section of Figure IV.

Figure VI is a plan of the card table.

Figure VII shows the table with its hinged legs partly folded.

Figure VIII shows a sliding tray fitted to a card table.

Figure IX is a vertical section of Figure VIII.

Figure X shows a sliding tray in a chair arm.

Figure XI shows an invalid table associated with trays in the arms of a chair.

Referring to Figures I and II, 2 indicates the arm of an arm chair. At the outer and upper corner of the arm is mounted the occasional rest consisting of the tray 3 of suitable size to receive such article as a cup and saucer, a tumbler, a box of cigarettes or the like. The tray comprises the base 4 and the rim 5, which latter is continuous about the base, or materially so. The tray 3 is constructed as two leaves 3a, 3b which are permanently connected to one another by the pair of hinges 6. The axis 7 of the hinges is level with the upper surface 8 of the rim 5.

One half 3a of the tray is fixed to the framework 9 of the chair arm in a horizontal position and with its rim upward; and also with its hinge axis 7 about in the plane of the outer surface 10 of the arm 2, so that the movable leaf 3b can be opened out to the projected position of Figure I or folded over the leaf 3a as indicated in Figure II. In the Figure I position the leaves are aligned horizontally to constitute the usable tray 3 with the inner end faces 11 of the leaves in contact; and giving to the hinged joint the rigidity due to the full depth 12 of the tray (including the rim) being available as an arm of a bell crank lever pivoted at the axis 7 to resist torque due to the weight of the article on the arm represented by the leaf 3b. Since the axis 7 is in the plane of the surface 8 when the tray is folded, both faces 11 are level with the outer surface 10 of the arm. In the folded position the leaf 3b lies over the leaf 3a and conceals the whole tray as such.

The leaf 3a is stepped down from the adjacent upper surface 13 of chair arm 2; and the leaf 3b is made, either by itself or with additions, of the same thickness as the depth 14 of the step. Accordingly when the tray is folded, the back surface 15 of the leaf 3b is level with the surface 13 and forms therewith the complete upper surface of the arm in conformity with normal chair form. Similarly the end face 16 of the leaf 3b and its side face 17 conform respectively with the inner face 18 of the chair arm and the front face 19 thereof.

Said structurally conforming surfaces are also made to conform in appearance so that upon casual inspection the arm does not differ from the normal arm in which the upper and outer corner is integral with the rest of the arm. That is to say if the arm exposes a wooden top surface the back of the leaf 3b may be a piece of the same wood.

In the example shown, the chair is upholstered and the presence of the tray necessitates the upholstery around the tray being cut. In order to dispose of the cut edges in a workmanlike manner, the leaf 3a of the tray 3 is sunk level with a raised edge 20 forming part of the arm structure and surrounding the leaf 3a at the inside and end of the arm. The cut ends 21 of the inside and end panels of the upholstery are pulled over said edge 20 and secured inside the latter. The cut end 22 of the upholstery panel at the outside of the arm is secured to the surface 23 on which the leaf 3a rests; and said leaf 3a covers said end 22 and said surface 23.

A corresponding arrangement is provided for the leaf 3b. That is to say, said leaf 3b is closed

in at two sides and at its back by a block 24 of material, which is soft or hard as desired. This block is covered with the upholstery material and the loose ends 25 of the latter are enclosed between the tray 3b and the block 24.

The open end 26 of the folded tray directly between the hinges 6 is suitably covered over, conveniently by a piece 27 of flexible sheet material such as the upholstering material. Said piece 10 is secured to lie against the back faces 28, 29 of the base of the tray and not fixed to the end faces 11, so that when the tray is extended, said piece does not interfere with the mutual contact of said end faces, but hangs as a loop 30, Figure II.

Figures III to VII show the folding tray applied to an article of furniture of the table type—which includes desks—and which in the example is a card table. Figure VI shows the preferred disposition of four trays 31, viz. near to the left hand end of each table edge 32, so as to be easily accessible to the right hand of a person who sits facing the table edge that is to the left of the table edge at which the tray is fitted.

25 33 indicates a sheet of plywood forming the table top and covered with a sheet 34 of baize. 35 is the usual wooden frame surrounding the table top and constructed of sticks considerably thicker vertically than the sheet 33. According 30 to the invention, the sheet 33 is cut through at the edges 36 and the adjacent frame member 35 is cut down to form the notch 37 of the sill 38. A spacing frame 39 is fitted to the undersurface 35 of 33 and around the edges 36; and the leaf 3a of the tray 3 is secured to said sill 38 and said frame 39. Said leaf 3a is secured to the sill 38 at such a depth below the table surface that the back 40 of leaf 3b is level with said surface when 3b is folded over 3a as shown in Figure V. The back 40 of leaf 3b is moreover covered with baize 34a, so that it completes the normal playing surface of the table. If the customary vertical depth of the frame 35 is adhered to, the vertical depth 15 of the tray may not be sufficient to give adequate rigidity at the hinged joint. In that case it is preferred to provide additional means for supporting the leaf 3b in its out-turned position, such as the ledge 41 which is fixed to the sill 38 for said leaf 3b to come to rest on.

50 For good appearance it is preferred to inlay a strip of wood 42 that appears as a continuation of the upper surface 43 of the members of the frame 35. 44 is a tab positioned between said strip 42 and the baize 34a to assist in lifting the folded-over leaf 3b. The usual hinged legs 45 of the card table are notched at 46 to allow 55 said legs to be brought to their regular stowed position under the table top notwithstanding the presence of the trays and associated additional structure also under the table top.

A card table fitted with one-piece sliding trays 47 is shown in Figures VIII and IX. Said tray 47 comprises the base 48 and continuous rim 49 formed as an end element of a rigid flat sliding member 47, 50. Said member 47, 50 slides horizontally in the pair of guides constituted by the underside 51 of the table top 33 and by other supporting members such as the angle bars 52. The tray portion 47 is stepped down from the 60 portion 50, forming a shoulder 53.

70 A rectangular gap 54 is cut through the adjacent frame member 35 for the tray to slide through; and said shoulder 53 contacts with the portion 55 of said frame member 35 above the gap 54, to form a stop that limits the extending

movement of the tray. The block 56 secured to the underside 51 of the table top 33 forms a second stop determining the inward or stowed position of the tray to that at which its end surface 57 is flush with the surface 58 of the frame 35.

Figure X shows a one-piece sliding tray associated with the arm 2 of a chair, in such a manner that the horizontal outward extension of the projected tray is fore-shortened to be accommodated within the width of the arm when the tray is stowed away. A chamber 59 is constructed within the thickness of the arm 2, having communication with the exterior through the rectangular aperture 60 in the outer side wall of the arm, defined by the frame 61. The chamber is provided with a sloping floor 62 against which the tray 63 falls and lies upon being pushed into the chamber 59 as shown by the dotted lines. At the lower end of the floor is the stop 64 against which the end 65 of the tray falls and which is so positioned that, when the tray end 65 is resting against it, the section 66 of the tray rim at the outer end of the tray is within the aperture 60. The outer surface 67 of said rim section 66 is so shaped with regard to the tray base as to come flush with the side surface 68 of the arm; and said surfaces 67 and 68 may be given the same appearance.

Figure XI shows an arm chair each arm of which is provided with the folding tray 3 of Figure I. In connection with it there is provided an invalid table or book rest comprising a body 69 that spans the space between the arms and is provided with two feet 70 shaped to support the 35 table or book rest stably by fitting into the tray leaves 3a. For this purpose each foot is formed to rest on the base of the tray and is of rectangular shape in plan; and of such horizontal dimensions as to fit snugly within the rim of the tray.

We claim:

1. A chair the general shape of which conforms to that of chairs in common use comprising a seat, a side arm, the front portion whereof is stepped downwardly in elevation from the adjacent upper surface of the arm; and a tray suitable for the support of light articles and having a materially continuous rim; said tray being formed in two parts so hinged to one another as to provide two leaves foldable or unfoldable with respect to one another to bring the tray into a stowed or an extended position; one leaf being so fixed to said arm in a horizontal position in

the said stepped down portion thereof, that, in the extended position of the tray, the tray projects outwardly from said arm away from said seat and within easy reach of a person sitting on said seat; and so that in the stowed position of the tray, it fills the step in said arm and presents its back surface in continuation of the said adjacent upper surface of said arm, to conform the shape of such arm to that of chairs in common use.

2. The chair claimed in claim 1 in which said back surface of the folding leaf accords in appearance with the unstepped portion of said arm.

3. The chair claimed in claim 1 in which said side arm is upholstered, except in said stepped down portion of the arm, the stepped down portion of the arm comprising a recess with a horizontal floor, the depth of the recess being equal to that of the fixed leaf and the fixed leaf being arranged in the recess and fixed therein; the cut edges of the upholstery terminating at the stepped down portion of the arm being concealed by being turned into the recess and sandwiched between the recess walls and the fixed leaf; the folding leaf comprising a body member the back surface of which, when the leaf is in folded position, conforms to the arm contour leaf, and a lining member attached to the body member which provides the floor of that part of the tray provided by the leaf; the said back surface of the body member being covered with upholstery the cut edges of which are concealed by being inserted and attached between the body member and the lining member.
